VENTILATED RIB STRUCTURE FOR
GUN BARRELSArne Y. Grahn, Hartford, Conn., assignor to The Poly
Choke Company, Incorporated, East Hartford, Conn.,
a corporation of ConnecticutFiled Jan. 5, 1961, Ser. No. 80,844
9 Claims. (Cl. 33—47)

This invention relates to sighting ribs for gun barrels, and relates more particularly to a sight rib of the ventilated type which, while not limited thereto, is particularly well suited for employment on a single-barrel shotgun. Sighting ribs are commonly ventilated to increase the dissipation of heat therefrom, which heat, of course, is generated in the gun barrel through repeated firing of the gun and transferred from the barrel to the rib by conduction. It has been found that if there is insufficient dissipation of thermal energy from the sighting rib, visible heat waves radiate from the rib and interfere with the shooter's sighting vision; hence, in addition to ventilating sighting rib structures, it has often been found desirable to construct the rib of a material, such as aluminum, for example, characterized by high heat conduction to increase the dissipation of heat from the rib structure. As ventilated rib structures formed of such materials as aluminum, for example, cannot be welded to steel gun barrels due to differences in the characteristics of the metals, these rib structures must be attached to steel gun barrels by mechanical means, and it is known that many difficulties have been encountered in the past in securing these rib structures to steel barrels.

One object of the invention is to provide an improved ventilated rib structure which is light in weight and which will not impair the balance of the firearm to which it is attached.

Another object is to provide a ventilated rib structure characterized by improved means for releasably securing the structure to the barrel of a firearm in such a manner that the structure is held firmly in place and may be easily removed when desired.

Still another object is to provide a ventilated rib structure characterized by economical and convenient means for securing the structure to a gun barrel.

To these and other ends, the invention resides in the novel features and combinations to be hereinafter described and claimed.

In the accompanying drawing:

FIG. 1 is a fragmentary side elevational view of a ventilated rib structure embodying the invention and illustrating the same in association with a single-barrel shotgun;

FIG. 2 is an enlarged fragmentary view further illustrating the rib structure in side elevation, and showing the same secured to the gun barrel;

FIG. 3 is a top plan view of the rib structure attached to the gun barrel;

FIG. 4 is an enlarged, broken sectional view taken on line 4—4 of FIG. 3; and

FIG. 5 is a sectional view taken on line 5—5 of FIG. 4.

In the drawing the barrel of the shotgun is indicated generally at 10, and the ventilated rib structure generally at 11. The rib structure is preferably formed of a material characterized by high thermal conductivity to rapidly dissipate heat therefrom, a material such as alu-

2

minum, for example. If aluminum is used, it may be anodized to give the material color when color is desired. However, where it is found desirable for one reason or another, the rib structure may be constructed of other materials, such as suitable plastics, perhaps nylon, for example.

As best shown in FIG. 2, the rib structure is slotted, as at 12, for ventilation purposes, these slots extending transversely through the structure and being arranged at close intervals lengthwise of the barrel 10. This slotting of the elongated structure provides in the structure a strip-like upper part 13 supported and spaced upwardly from a strip-like lower part 14 by integrally formed posts 15 spaced axially of the structure at relatively long intervals. In the illustrated form, these posts are generally of diamond shape in cross-section, having two blunted points arranged at the respective sides of the rib structure.

As best indicated in FIG. 4, the sides 16 of each post 15 are of concave form. Substantially midway between each post 15 and the next post 15 the lower strip 14 of the rib structure is provided with a vertical bore 17 extending therethrough and having its lower end enlarged as at 18. To secure the rib structure to the gun barrel a plurality of threaded steel studs 19 extend upwardly through the respective bores 17, the studs having heads substantially recessed in the outer wall of the gun barrel and secured therein as by welding.

The lower face of the strip part 14 is contoured as at 20 throughout its length to fit closely to the gun barrel 10. The upper threaded ends of the studs 19 receive nuts 21 disposed between the upper and lower strip parts of the rib structure and clamping the lower strip firmly against the gun barrel. It will be noted from the foregoing that the studs 19 are permanently secured to the gun barrel and are spaced along the length thereof to register properly with the bores 17 provided in the rib structure. In the illustrated form, the nuts 21 which receive the threaded upper ends of the studs 19 are of a depth to substantially occupy the space between the upper and lower strip parts of the rib structure, as indicated in FIG. 2. As indicated in FIGS. 3 and 5, the upper surface of the strip part 13, which provides the sight part of the rib structure, may be provided with small longitudinal grooves to lessen light reflection from this surface, and on the upper surface of the strip part 13 at the forward end of the rib structure a conventional sight bead 22 may be mounted.

The rib structure may be easily removed from the gun barrel for replacement, for example, or for work on the gun barrel. A simple wrench, such as that shown in broken lines in FIG. 3 and indicated at 23 may be used for this purpose. The slots in the rib structure provide sufficient clearance for the wrench for the rapid and easy removal of the nuts 21. The rib structure may be easily remounted by replacing the nuts in the respective slots 12 in such a manner that the nuts register with the respective bores 17. The nuts may be held in these positions by slightly squeezing the upper and lower strip parts of the rib structure together. As the nuts are dimensioned to fit closely between the upper and lower strip-like parts of the rib structure, relocation of the structure on the gun barrel is facilitated, as the nuts 21 tend to remain in alignment with the respective bores 17 extending through the lower strip part. When the nuts 65 are properly positioned, the rib structure may be lowered

on the studs 19 and the studs aligned with the bores 17 and the respective nuts, and when the nuts are properly seated on the upper threaded ends of the studs the nuts may be turned with a wrench until they securely clamp the rib structure to the gun barrel.

From the foregoing disclosure, it will be manifest that there is provided an improved ventilated rib structure which may be constructed of a material characterized by high thermal conductivity to reduce or tend to eliminate heat waves radiating from the structure, and which tend to interfere with a shooter's sight vision. It will be apparent that the rib structure may be constructed from one of a number of materials, and in this connection it will be obvious from the foregoing that the rib structure may be light in weight so as not to impair the balance of the gun. It will be further appreciated that the rib structure is provided with improved means for securely fastening the rib structure to the gun barrel. In this connection it should be noted that the fasteners are located at points remote from the posts, which space and secure the upper and lower riblike parts of the rib structure together. Also, in this connection it should be noted that the lower strip part of the rib structure provides a surface continuous throughout the length of the structure for engagement with the gun barrel; in other words, a large bearing surface. Still another feature of the rib structure resides in the provision of simple and yet effective means for releasably securing the rib structure to the gun barrel.

While only one form of the rib structure has been illustrated in the drawing and described above, it will be apparent to those versed in the art that the rib structure may take other forms and is susceptible of various changes in details without departing from the principles of the invention and the scope of the appended claims.

What I claim is:

1. A ventilated sighting rib structure for a gun barrel, comprising a rib member having means defining transverse ventilating openings therein which are relatively long and arranged at short intervals to provide an upper strip-like part separated and supported from a lower strip-like part by a series of posts, and fastening means at points throughout the length of the rib member and remote from said posts, said fastening means including fastener elements extending through the lower strip-like part of the rib member to secure the latter to the gun barrel.

2. A ventilated sighting rib structure for a gun barrel, comprising a rib member having means defining transverse ventilating openings therein, a first series of fastener elements on the gun barrel and spaced apart lengthwise of the latter, a second series of fastener elements to co-act with the elements of the first series, the fastener elements of one series extending into the rib member and into at least certain of said ventilating openings, and the fastener elements of one series having parts lying within the last-mentioned openings and being accessible in these openings to secure each to the corresponding fastener element of the other series to clamp the rib member to the gun barrel.

3. A ventilated sighting rib structure for a gun barrel, comprising a rib member having means defining transverse ventilating openings therein of relatively long length, a first series of fastener elements on the gun barrel and spaced apart lengthwise of the latter, and a second series of fastener elements to co-act with the elements of the first series, the fastener elements of one series extending into the rib member and into at least certain of said ventilating openings, and the fastener elements of one series having parts lying within the last-mentioned openings and being accessible in these openings to secure each to the corresponding fastener element of the other series to clamp the rib member to the gun barrel.

4. A ventilated sighting rib structure for a gun barrel, comprising a rib member having means defining transverse ventilating openings therein of relatively long length

and arranged at short intervals, a first series of fastener elements on the gun barrel and spaced apart lengthwise of the latter, and a second series of fastener elements to co-act with the elements of the first series, the fastener elements of one series extending into the rib member and into at least certain of said ventilated openings, and the fastener elements of one series having parts lying within the last-mentioned openings and being accessible in these openings to secure each to the corresponding fastener element of the other series to clamp the rib member to the gun barrel.

5. A ventilated sighting rib structure for a gun barrel, comprising a rib member having means defining transverse ventilating openings therein of relatively long length and arranged at short intervals to provide a series of posts spacing and supporting an upper strip-like part from a lower strip-like part of the member, a first series of fastener elements on the gun barrel and spaced apart lengthwise of the latter, and a second series of fastener elements to co-act with the fastener elements of the first series, the fastener elements of one series extending through the lower strip part of the rib member and into at least certain of said ventilating openings, and the fastener elements of one series having parts lying within the last mentioned openings and being accessible in these openings to secure each to the corresponding fastener element of the other series to clamp the rib member to the gun barrel.

6. A ventilated sighting rib structure for a gun barrel, comprising a rib member having means defining transverse ventilating openings therein of relatively long length and arranged at short intervals, providing posts spaced from one another along the gun barrel and separating and supporting an upper strip part of the rib member from a lower strip part of the member, a first series of fastener elements on the gun barrel and spaced apart lengthwise of the latter, and a second series of fastener elements to co-act with the fastener elements of the first series, each fastener element of one series extending into one opening between two adjacent posts substantially midway between the posts and extending through the lower strip part of the rib member, and the fastener elements of one series having parts lying within the last-mentioned openings and being accessible in these openings to secure each to the corresponding fastener element of the other series to clamp the rib member to the gun barrel.

7. A ventilated sighting rib structure for a gun barrel, comprising a rib member having means defining transverse ventilating openings therein of relatively long length and arranged at short intervals to provide posts spaced along the gun barrel and separating and supporting an upper strip part of the rib member from a lower strip part of the member, a first series of fastener elements on the gun barrel and spaced apart lengthwise of the latter, and a second series of fastener elements to co-act with the fastener elements of the first series, the fastener elements of one series extending into the rib member through the lower strip part thereof substantially midway between certain adjacent ones of said posts, and the fastener elements of one series having parts lying within the last-mentioned openings and being accessible in these openings to secure each to the corresponding fastener element of the other series to clamp the rib member to the gun barrel.

8. A ventilated sighting rib structure for a gun barrel, comprising a rib member having means defining transverse ventilating openings therein of relatively long length and arranged at short intervals along the gun barrel, a series of upstanding threaded studs on the gun barrel in fixed relation thereto and spaced apart lengthwise of the latter, and a series of nuts to co-act with the studs, the studs extending into the rib member and into at least certain of said openings, and the nuts lying within the last-mentioned openings and being accessible in these openings for rotary movement to secure each to the

corresponding stud and clamp the rib member to the gun barrel.

9. A ventilated sighting rib structure for a gun barrel, comprising a rib member having means defining transverse ventilating openings therein of relatively long length and arranged at short intervals along the gun barrel, a series of upstanding threaded studs on the gun barrel in fixed relation thereto and spaced apart lengthwise of the latter, and a series of nuts to co-act with the studs, the

studs extending into the rib member and into at least certain of said openings, and the nuts lying within the last mentioned openings and being accessible in these openings for rotary movement to secure each to the corresponding stud and clamp the rib member to the gun barrel, the axial dimensions of the nuts being sufficient for the nuts to substantially fill the width of the openings in the rib member.
